FOLDING COUCH.

1,156,704.

Specification of Letters Patent.

Patented Oct. 12, 1915.

Application filed March 30, 1914. Serial No. 828,127.

To all whom it may concern:

Be it known that we, JACOB L. MOORE and FORY L. MUSSER, citizens of the United States, residing at Butler, in the county of Butler and State of Pennsylvania, have invented certain new and useful Improvements in Folding Couches, of which the following is a specification.

Our invention relates to folding couches, and the invention resides in the improved features of construction substantially as herein described and claimed, whereby the folding sections are locked and unlocked automatically when raised with that object in view, and whereby the folding sections are capable of being folded flat upon the top of the couch and the ends detached and nested within the main couch frame for compactness and protection in shipping.

In the accompanying drawings, Figure 1 is a perspective view of our improved couch with the side sections lowered, and Fig. 2 is an end view on a larger scale of the couch with the parts in the same position. Fig. 3 is an end view with the left-hand section raised to about the angle required to effect a locking action of the brace links, and the right-hand section is shown as partly lowered with the brace-links in striking relations with one leg of the frame. Fig. 4 illustrates the final rest and locked position of one side section (at the left) and also the positions assumed by a section when unlocking and lowering occurs (at the right).

Fig. 5 is a cross section, enlarged, on line 5—5, Fig. 3, showing the spring detent for the brace link. Fig. 6 is a plan view of the couch with the side sections folded inward on top of the main frame and its spring fabric and showing the ends of the couch in dotted lines and as nested between the springs, and Fig. 7 shows a side view of the couch and parts as related in Fig. 6. Fig. 8 is an end view of Fig. 6, and Fig. 9 is a view of one supporting end of the couch detached from the spring frame and with the braces folded to provide extensions for the legs.

The couch consists of a pair of bowed side rails 2 of angle-iron which are rigidly connected at their raised ends by cross pieces 3 of angle-iron. The upper or horizontal flange of each angle-iron piece 3 is formed at its ends with raised hinge portions 4

which have a pintle connection with similar 55 or equivalent raised hinge portions at the inner ends of the angle-iron pieces 5 of the side sections 6, whereby said side sections may be lowered and raised and adapted to swing in a circle of approximately two hundred and seventy degrees, or from a dropped and suspended position to a horizontal overlying position relatively to the main frame, see Fig. 8. A wire fabric or spring mesh bed bottom 7 is stretched in straight lines by 65 helical springs 9 between the angle-iron ends 3 and 5 of the main frame and its side sections, and when the side sections are folded in overlapping relations with the central or main frame the wire fabric on 70 the side sections rests upon and covers the wire fabric at the center of the main frame, or in other words, the wire fabric is doubled upon itself,—an advantageous arrangement in shipping as the couch is compacted 75 and the sectional frame and wire fabric is better protected by doubling its resistance to knocks and strains. The height of the couch is also greatly reduced when knocked down for shipping as the end supports 80 comprising the legs 10 and base piece 11 and the braces 12 are separably bolted upon the downwardly-extending flange of the angle-iron cross pieces 3 and by removing the bolts 13 the said end supports may be bodily 85 transferred and nested within the center of the main body of the couch between the doubled wire fabric 7 and the bowed side rails 2 as shown in dotted lines, Figs. 6 and 7. Spiral springs 14 are also used to sustain 90 the central portion of the wire fabric, said springs being supported in parallel rows transversely of the main frame by cross strips 15 of metal secured to the side rails 2, and the legs 10 of the end supports are projected between the said rows of springs when nested or packed within the main frame for shipping. However, legs 10 are not of sufficient length to permit their upper extremities to rest upon a side rail 2 100 when the said end supports are so nested, and for this reason the braces 12 are made of a predetermined length and pivotally secured by a rivet approximately midway of the height of each leg 10 to permit the braces 105 12 to be folded parallel with the legs 10 and to serve as extensions thereof so that the extremities of the braces will engage and

rest upon one side rail 2 when the lower ends of the legs are resting upon the other side rail 2, see dotted lines Fig. 6. The braces 12 for each end support are also mounted in the relations as shown and described to permit both braces to be jointly secured together and to the cross piece 3 by a single bolt 13 when the couch is assembled, see Fig. 2.

10 Necessarily, the folding side sections 6 require means to sustain them in a horizontal position when raised to convert the narrow couch to a wide bed, and the means which we have provided for this purpose is made 15 to operate automatically without requiring special effort or skill on the part of the operator to effect positive locking and unlocking of the parts, and it is also made with a view to permit the separable parts 20 of the structure to be easily disconnected and compactly folded for shipment. Referring to Figs. 2 to 5, the automatic locking means for each folding section 6 comprises a pair of pivotally connected links 16 and 17, hereinafter referred to as the brace link and pilot link, respectively. Brace link 16 is pivotally affixed at its outer end to the 25 inside face of one flange of the angle-iron 5 of the side section 6, and the pilot link 17 is provided with a key slot 18 at its outer end which permits a slidable and 30 detachable connection to be made with the headed rivet 19 on the outside face of the angle-iron leg 10. The head of the rivet is 35 of substantially the same diameter as the rounded opening of the key slot, and a close fit is preferred to prevent self-release of the parts during operations. The pilot link is held in flat engagement with the leg by the 40 head of the rivet 19, and the brace link 16 is pivotally secured to the leg-engaging face of the pilot link, which relationship of parts places the end edge 20 of said link 16 opposite the leg and permanently in position to 45 bear against the same when the brace link 16 is projected inwardly toward the leg as seen at the right in Fig. 3 and at the left in Fig. 4. Such projecting relation of link 16 is established when the folding section 50 6 is swung upwardly from its suspended position (Fig. 2) into an elevated inclined position as shown at the left in Fig. 3. The two links 16 and 17 are straightened or placed in end alinement by the lift action, 55 and buckling of the joint inward or toward leg 10 is then necessary to establish locking and bracing relations of link 16 with said leg. One way of producing the desired buckling action is to grip or hold the link 16 60 temporarily in fixed relations with the folding section 6 by means of a spring clip 21 affixed to the inside of angle-iron 5, see Fig. 5. Only a slight frictional engagement of the clip with the link is required to prevent 65 the link from dropping by gravity when the

folding section 6 is lowered and the result is that the end 20 of the link will travel inward and engage leg 10 the instant said section 6 is lowered,—a relationship of parts which is illustrated at the right in Fig. 3. 70 The weight of said section or pressure brought to bear thereon, will lower the section to the same horizontal level as the cross piece 3, and the link 16 will ride down the leg during this movement until a different 75 and better bracing angle of the link is established, or until the link 16 is checked in its down movement by pilot link 17 which has a limited sliding play on rivet 19. When the rivet rests in the upper end of the straight portion of the key slot 18 the pilot link 17 will support and hold the joint end 20 of link 16 in bracing engagement with leg 10, and as plainly shown at the left in Fig. 4. Link 16 is also disengaged from 80 clip 21 when it is forced into its angular bracing relationship with leg 10, and therefore when a slight upward lift is imparted to the section 6 as shown at the right in full lines in Fig. 4, the pilot link 17 will be carried in an outward direction until both links reach a dead center and then the weight of the links causes a buckling or folding movement thereof which permits the side section 6 to be lowered as illustrated by the dotted 85 lines in Fig. 4.

The operation of folding and unfolding the side sections is exceedingly simple, and locking and unlocking of the parts is entirely automatic. In unfolding operations, the 100 side section 6 is merely lifted to the stop limits fixed by the links and then lowered, which movement places the section in a horizontal position and in braced relations with the main frame. No special effort or 105 skill is required to accomplish the desired result, and the locking devices at both ends of the sections are operated simultaneously and positively, regardless of any twist in the frame or difference in play between 110 the ends of the sections. Unlocking and lowering of the side sections also requires no special effort or skilful manipulation of the sections, as a slight initial uplift 115 causes the links to drop by gravity out of their bracing relations with the frame.

What we claim is:

1. In a folding couch, a frame, a hinged side section, a pair of links pivotally connected with each other and with said frame and section respectively, and a spring clip adapted to engage and hold said links in buckled relations during folding movements of said section. 120

2. In a folding couch, a frame, a hinged side section, a brace link pivoted to said section, a pilot link pivotally connected with said brace link and adapted to have a slidable connection with said frame, and a spring clip upon said section to engage and 125 130

hold said brace link during folding movements of said section.

3. In a folding couch, a frame, a hinged section, a brace link connected with said section, a pilot link connected to said brace link having a slotted end detachably and slidably connected with said frame, and means to effect a reverse buckling movement of the links upon a lowering folding movement of said section.

4. A couch frame having a folding section and a pair of pivotally-connected links

at each end of said section connected with said frame and adapted to have limited sliding contact at their ends on said frame, said links being adapted to be buckled when said section is in use.

In testimony whereof we affix our signatures in presence of two witnesses.

JACOB L. MOORE.
FORY L. MUSSER.
